IGNITION CONTROL MECHANISM

Alphonse V. Alvino, Newark, N. J., assignor to
Bendix Aviation Corporation, South Bend, Ind.,
a corporation of Delaware

Application June 15, 1942, Serial No. 447,131

6 Claims. (Cl. 123—148)

This invention relates to internal combustion engines, and particularly to the ignition of fuel in the engine cylinders, for combustion and power development therein.

An object of the invention is to provide a novel method of ignition production and control, for use in internal combustion engines.

Another object is to provide a novel ignition system, including a novel electrical circuit, and novel electrical elements entering into the operation of said circuit.

Another object is to provide a novel ignition system, including novel structural features in the component parts, which features are believed to be patentable, *per se*, as well as in the combination disclosed.

These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing,

Fig. 1 is a schematic representation of the invention;

Fig. 2 is a central sectional view of the "booster" unit;

Fig. 3 is a view to the right of Fig. 2; and

Fig. 4 is a view to the left of Fig. 2.

The most common type of aircraft engine ignition system involves the use of a magneto-electric-generator (hereinafter called a "magneto") mechanically driven from the engine crank-shaft, and generating in its secondary winding, a high tension current for delivery to the engine spark-plugs by way of a rotary distributor, the latter being also driven from the engine, and usually involving a pair of rotatable, angularly spaced distributor "fingers," or brushes, one of which is directly in circuit with said secondary magneto winding, while the second distributor "finger" or brush, is in a circuit leading back to a "booster" ignition device—either a second (starting-motor-operated) magneto or a battery-energized induction coil—whose secondary winding feeds "booster" current to said second distributor finger (as shown at 30 in Nowosielski Patent No. 1,921,427, granted August 8, 1933), and thus constitutes a parallel, alternative source of ignition (usually confined to the brief engine-starting period, when crank-shaft speed is low).

The present concept is to substitute, for the above-described Nowosielski method of connecting the "booster" unit, a method of connection wherein both the "booster" unit and the standard, or "service" magneto unit will function as complementary, rather than as alternatively operating units, and wherein the "booster" unit will service as a source of additional energy for the magneto, and in such manner as to render the magneto capable of supplying adequate ignition current under all conditions of engine speed and all conditions of aircraft operation, including both high and low altitude flying.

I accomplish these results by providing a series 15 circuit type of connection from the secondary winding 11 (Fig. 1) of the "booster" 12 to the primary winding 13 of the magneto; the primary winding 10 of the "booster" being energized from battery, upon closure of manually operable 20 switch 17. As shown in Figs. 2, 3 and 4, there is a vibrator type of contact mechanism at the right-hand end of the booster, including resilient arm 18 carrying a contact button 19; the resiliency of arm 18 being such as to hold button 25 19 in contact with button 20 until sufficient current flows from source 16 through windings 10 and 11 to develop a magnetic pull of sufficient strength to withdraw 19 from 20. The magnetic pull, of course, is by way of core 21 forming part 30 of the magneto circuit, as in all vibratory induction coils. The engine-driven breaker operating cam 26 periodically separates contact 27 from contact 28, as in standard practice, and condenser 29 functions as in standard magneto circuits; except that its capacity will now be greater, 35 due to the added energy derived from the action of booster 12. Distributor 31 will be as in standard practice, except that a single rotating brush 32 will now suffice, where two have been used heretofore. Each distributor point will connect with a different spark-plug, there being only one spark-plug shown (at 34), to indicate the manner of connection of all. A hand-switch 35 will serve to "ground" the magneto circuit (as is 40 standard practice) until it is desired to start the engine, at which time switch 35 will be moved to the "on" position.

In order to prevent a drain-back (to ground) 45 of current generated in windings 13, 14, during such times as contact parts 27, 28 are closed (and switch 17 is open), I interpose, between 11 and 13, a switch 41, 42 whose contact 42 is biased to the open position by an adjustable spring 43, but is movable to the closed position each time coils 50 10, 11 are energized and said contact 42 will re-

main in closed position until switch 17 is manually opened to discontinue energization of coils 10, 11. In other words, the position of contacts 42, 40 is determined by the position of switch 17, both as to closing and opening. Thus a feedback, from 13 to ground 50, is rendered impossible.

The use of the double winding 10-11 prevents the flow of current from the battery 16 through the main magneto in case of sticking of the contacts 19 and 20.

Fig. 2 shows the core 21 as it appears before being filled with the conventional iron rods or wires, to constitute the usual induction coil type of solid core (as in Allen Patent No. 2,096,664 granted October 19, 1937) which is desirable for most efficient magnetic co-action with both the armature 18 and the armature 41.

I claim:

1. In an internal combustion engine ignition system, the combination, with a storage battery, of a plurality of spark-plugs and an engine driven magneto having primary and secondary windings in circuit with said storage battery and spark-plugs, in such manner that the magneto may receive energy from said storage battery upon closure of said circuit, engine-driven means for periodically interrupting the current delivered to said primary winding by said magneto electrical means for concurrently producing interruption of such current from said battery at a rate which is independent of the rate of interruption produced by said engine-driven means, and electromagnetic means associated with said electrical means for causing the latter to automatically break the circuit from said battery when said engine has achieved a predetermined rate of speed.

2. The combination, with an internal combustion engine spark-plug, and a high-tension circuit leading thereto and operable to render said spark plug effective during the entire period of operation of said engine, of means for boosting the intensity of the current in said circuit, said means comprising an induction coil having low-tension primary and low-tension secondary circuits, means for coupling said low-tension secondary with the high-tension circuit leading to said spark-plug, and means for preventing the grounding of said high tension circuit when said boosting means is cut out.

3. The combination, with an internal combustion engine spark-plug, and a high-tension circuit leading thereto, of means for boosting the intensity of the current in said circuit, said means

comprising an induction coil having low-tension primary and low-tension secondary circuits, and means for coupling said low-tension secondary with the high-tension circuit leading to said spark-plug, said last-named means including a magneto having its primary winding in connection with said induction coil secondary circuit, a switch for cutting out said boosting means, and a second switch between said low tension secondary and said magneto primary and automatically operable coincident with operation of the first said switch.

4. The combination, with an internal combustion engine spark-plug, and a high-tension circuit leading thereto, of means for boosting the intensity of the current in said circuit, said means comprising an induction coil having low-tension primary and low-tension secondary circuits, means for coupling said low-tension secondary with the high-tension circuit leading to said spark-plug, a magneto having an engine-driven circuit-breaker and contacts operated thereby, said contacts being interposed between said magneto and said high-tension spark-plug circuit, and a switch included in said coupling means and automatically operable upon cutting out of said booster means to break the circuit between said high tension circuit and said low tension secondary.

5. The combination, with an internal combustion engine spark-plug, and a high-tension circuit leading thereto, of means for boosting the intensity of the current in said circuit, said means comprising an induction coil having low-tension primary and low-tension secondary circuits, means for coupling said low-tension secondary with the high-tension circuit leading to said spark-plug, a magneto having its primary winding in series connection with said induction coil secondary circuit, and an engine-driven circuit-breaker for periodically interrupting the current delivered from said magneto to said high tension circuit.

6. In combination, an internal combustion engine including a spark plug, a magneto operatively driven by said engine and connected to said spark plug to supply electrical current thereto, a battery, means for delivering current from said battery to said magneto to supplement the current generated thereby, and means for cutting out the last said means and at the same time breaking the circuit from said battery to said magneto to prevent grounding of said magneto.

ALPHONSE V. ALVINO.
